TRAVELING BLOCK CONSTRUCTION

Harry Talmage Nichols, San Antonio, Tex.

Application September 29, 1930, Serial No. 485,276
Renewed May 21, 1935

44 Claims. (Cl. 254—192)

My invention relates to traveling block construction. It has to do particularly with the provision of a traveling block having various features of novelty which combine to overcome serious disadvantages hitherto prevalent in traveling blocks.

In order to adequately disclose the novelty of various features of the present invention, I will first describe the principal features which characterize previously known traveling block constructions.

Previously known traveling block constructions, as utilized in the extremely heavy operations incident to the drilling of wells, have consisted of a plurality of elongated metal plates disposed in parallel, spaced apart relation to each other, including outer, or cheek, plates, and inner plates disposed intermediate the former to constitute a framework to house and rotatably support sheave means disposed in the spaces between the sides of adjacent plates.

In previously known constructions the lines which bound the extremities of the sides of the frame plates that face toward the central planes of the sheaves to which they are respectively adjacent are characterized by their being spaced in a sidewise direction away from the side edges of the rims of the sheaves to permit the free rotation of the latter.

30 The inner frame plates have been of straight uniform section throughout their length, and the thickness of the section which is normal to them is established by calculating the distance between the extremities of the plane face sides of the sheaves between which they are disposed and subtracting the dimension requisite to provide the working clearance to permit the free rotation of those sheaves.

Usually the outer, or cheek, plates have been 40 of straight uniform section in which case they have been, latterly, and generally, supplemented by outer plate or bar formations projecting outwardly from their outer sides to form the cheek extremities of the traveling block.

45 In other known constructions the outer, or cheek, plates, while not of uniform section throughout their length, and sometimes having integrally formed reinforcing ribs or other boss-like formations on their sides which face toward the central planes of the sheaves to which they are adjacent, are so disposed that the lines which define their extremities which face toward the central planes of the sheaves to which they are adjacent (which lines, therefore, are the normal lines defining those sides thereof) are also spaced

in a sidewise direction away from the planes coincident with the side edges of the rims of the adjacent sheaves.

Opposite end edges of the frame plates are apertured to receive pins which pass therethrough 5 to secure becket members which have eye portions disposed in interlaced relation therewith.

The becket on the upper end of the block, which may be or may not be mounted to pivot thereon, is for the anchoring of the standing 10 part of the compound pulley hoisting cable rove through the grooves of the sheave means of the traveling block.

The becket on the lower end of the block is the load supporting becket, and this becket is 15 intended to pivot freely on the becket pin which supports it in interlaced relation with the lower end edges of the frame plates of the block.

The spacing of these lower edges is calculated 20 to allow a working clearance between the plane sides of the eye portions of the becket and the portions of the lower end edges of the frame plates which abut them.

Intermediate the becket pin apertures at either 25 end of the frame plates are other apertures therethrough for the reception of means to rotatably support the sheave means.

This first said means usually consists of a fixed 30 center pin or shaft which extends through the hubs of and supports one or more sheaves, although in some constructions independently rotatable means for supporting each sheave is provided.

The ends of the becket pins and the center pin or shaft, if the latter is used, are secured on the 35 outer sides of the outermost plates, or strap members, of the framework by means of nuts or other relaxable means which seat against outer flat surfaces thereof, which latter are at right angles to the axes of the sheaves of the block. 40

The spaces between the end edge portions of the plates not occupied by the eye portions of the beackets are occupied by spacer elements which are usually carried on the becket pins, which latter, apart from carrying the becket members, 45 also serve to hold the frame plates against separation.

I have conceived the idea that these prior art traveling blocks are of such construction that they possess numerous disadvantages from a practical 50 standpoint.

This invention remedies these disadvantages.

One of these disadvantages arises from the fact that prior traveling block constructions have been made of unnecessary length.

One reason for this has been the tendency to adhere to the usual provision of an anchor for the dead line or standing part of the hoisting line on the traveling block in the form of a becket attached to the top thereof.

5 Another reason for this has been the attempt to offset the tilting tendency of the traveling block, a tendency which is proportionately cumulative with each additional sheave in the traveling block, by adding to the length of the portion of the block framework which is below the axis of the sheave means thereof, in comparison with the length thereof above the said axis, thereby producing what is known as "underslung" construction.

10 In traveling blocks of the so called "underslung" type the length of the framework is usually equal to double or more the rim dimension of the sheave means of the block.

15 Another disadvantage inherent in prior art traveling blocks has arisen from the customary practice of utilizing the pin which connects the lower load supporting becket to the traveling block for the additional function of securing the lower 25 end of the frame plates of the traveling block against separation.

In oil field operations, it frequently becomes necessary to remove this lower becket pin so that the lower becket may be removed for disconnection from and connection to the particular type 30 of apparatus which is to be supported thereby.

These traveling blocks are ordinarily used under extremely heavy loads, and when a new traveling block is placed in service and subjected to these 35 loads imperfections in agreement and alinement between the parts, which are inevitable in commercial manufacture, bring about a realinement and accommodation therebetween which subsides when a working mean becomes established.

40 The stresses imposed on the portions of the frame plates between the sheave supporting apertures and the lower end edge portions thereof which surround the load-supporting becket pin apertures during this process of realinement under load, and particularly on the straight section, 45 inner plates, which are devoid of reinforcing, often exceed the elastic limit of the metal of the plates, and tend to produce a warped or distorted condition which destroys the alinement and spacing of these lower end edge portions.

The starting and subsequent spreading of these 50 distortions, which culminate in a misaligned, mis-spaced condition in these lower edge portions of the frame plates, are induced by the lack of a unitary, firm, rigid spacing and binding together of these lower end edge portions of the inner and outer frame plates which would tend to prevent the development of such a condition.

60 The spacing and binding of these lower end edge portions of the frame plates has, in all previous constructions, been merely nominal, inasmuch as the mere holding against separation by a becket pin which permits the interlaced eye 65 portions of the becket to move freely relative to the portions of the several frame plates which abut them cannot, because of this very fact, be effective to resist and prevent the development of warping and distortion.

70 The warped and distorted condition thus produced in these lower end edge portions of the frame plates operates, in fact, to produce a binding effect between the plane faces of the eye 75 portions of the becket and the abutting portions of

the plates which prevents the free pivoting of the former.

The mentioned warping and distortion also produces a binding action between the straight walls of the apertures through the plates and the 5 becket pin installed therein, which binding action necessitates severe driving by repeated heavy blows against the threaded end of the becket pin to disassemble it.

Under these conditions, which are the rule and 10 not the exception, the reassembly of the becket and its pin present even greater difficulty, and this difficulty becomes cumulatively greater each time the becket is disassembled from the framework.

15 Another disadvantage in prior art traveling blocks has arisen from the fact that, owing to the extremely heavy loads to which these traveling blocks are subjected in oil well drilling operations, it has been customary, in order to utilize the full 20 strength of the stock of the sheave supporting frame plates thereof, to provide apertures therethrough having straight walls which extend across the full normal section of the metal thereof for the reception of the becket pins.

25 These becket pins are so closely fitted to the diameter of the apertures in which they are installed that expert mechanics are required in the shop to assemble them, this being particularly so because of the fact that each becket pin is ordinarily provided behind its threads with a shoulder of such angular form that it will not readily enter the close fitting apertures in the plates, the lips of which are also of the same angular form as the shoulder on the pin.

30 Another disadvantage has arisen from the fact that, in the effort to provide the traveling block with side surfaces devoid of angular projections or protuberances, which might engage and foul objects passed by the block during operation, it 40 has been customary to shelter the heads and nuts of the becket pins and the center pin or shaft in recesses formed in the outer sides of the outer plates having a greater diameter than the nuts 45 sheltered therein.

45 Sometimes this desired result has been obtained by providing supplemental reenforcing plates or bars on the sides of the traveling block, these reenforcing plates or bars likewise containing similar recesses in which the heads and nuts of the 50 becket pins and the center pin or shaft are sheltered.

55 Where these recesses are provided in the cheek plates, the over-all thickness of these plates must be increased to provide for the depth of the recesses which, by reason of their diameter being superior to that of the nuts sheltered do no useful work, and this results in a traveling block of increased width.

60 Where outside reenforcing plates are used, it will be obvious that the width of the traveling block is also increased.

65 One of the objects of my invention is to provide a traveling block of greatly decreased length in proportion to the size of the sheaves which will be adequately supported, and which will, also, adequately offset and overcome the tilting tendencies inherent in traveling blocks.

70 Another object of my invention is to provide a traveling block of such construction that the 70 load supporting becket pin thereof may be removed and replaced at will without hindrance from distorted plates or parts.

75 Another object of my invention is to provide a means for facilitating the rapid and easy inser-

tion of the lower becket pin into the interiorly disposed ends of the straight walls of the apertures through which it must pass in order to effectuate the securing of the load supporting becket in operative position, while maintaining the straight walls of those apertures across the full normal section of the metal of the becket supporting frame plates.

A still further object of my invention is to provide a traveling block with side surfaces free from angular projections or protuberances without the necessity for materially increasing the width of the traveling block, and at the same time to shelter the nuts of the pins so as to employ edges 15 of the nuts themselves in such a manner that the greater portion or all of the stock of the metal of the outermost members of the framework is utilized for useful work.

My invention preferably contemplates the provision of a traveling block wherein the over-all length thereof is but slightly greater than the rim diameter of the sheaves, this being mainly accomplished by two features.

One of these features arises from the fact that I 25 preferably entirely dispense with the conventional upper becket of the traveling block and provide means for connecting the standing part of the cable to the traveling block within the area below the top of its sheaves.

Another of these features arises from the fact that I construct sheave supporting frame plates of my traveling block in such a way that their weight below the axes of the sheaves is predominantly greater than the weight thereabove by materially increasing the cubical contents of a substantial portion of the area thereof below the said axes and without increasing the length there- 35 of.

My invention also preferably contemplates the provision of means for exactly spacing and rigidly binding the sheave supporting frame plates of traveling blocks which is effective, under all conditions of use and manipulation of the other parts of the block, to resist the tendency of these plates 45 to warp and become distorted, and to maintain this rigidly bound exactly spaced relationship.

This provision of means is especially important in and between the lower and edge portions of the frame plates through which the load supporting becket pin apertures are formed, since it permits the load supporting becket to, at all times, pivot freely on the pin which supports the eye portions thereof in interlaced relationship with these lower edge portions of the frame plates, and obviates the difficulties resulting from misalignment of these becket pin apertures which commonly attend the operation of disassembling and reassembling the becket from and to operative load-supporting position.

A further feature of my invention consists in the fact that I have provided the ends of the straight walls of the becket pin apertures, on either side of the inner frame plates, and on the inner sides of the outer frame plates, with funnel shaped mouths which are formed in projecting extensions constituting boss formations at these portions of the frame plates.

These funnel shaped mouths which flare increasingly from the ends of the straight walls of the apertures through the frame plates to the outer extremities of the boss formations in which they are formed will be effective to progressively guide the becket pin into operative position in its supporting apertures and will obviate prevalent

delays by permitting the rapid and ready insertion of the becket pin into assembled position.

The binding pin apertures through the frame plates are, preferably, likewise provided with similar boss formations which have similar funnel shaped mouths to facilitate the assembly of the entire sheave supporting plate structure of the block.

It will be obvious that these tapered, funnel-shaped mouths being formed within projecting extensions provided at these portions of each sheave-supporting frame plate, the full strength of the normal section of the plate is conserved by maintaining the straight walls of the apertures across the full normal section thereof.

It will, furthermore, be obvious that the necessity of chamfering the stock of the normal section of the frame plates, with a consequent reduction of the area of the straight walls of the apertures, and of the effective strength of the plates, 10 for the reception and support of the close fitting pins, to facilitate the entry of the angular shoulders of the pins, is thereby obviated.

A still further feature of my invention arises from the fact that my traveling block is so constructed that the nuts of the becket pin and shaft 25 may be located in recesses in the outer plates, which recesses are tapered to form seats for the reception of tapered nuts which are designed to be screwed into seating contact with the tapered walls 30 of these recesses.

This will result in utilizing the greater portion or all of the walls of the recesses and consequently the greater portion or all of the stock of the outer plates for useful work and will, therefore, decrease the necessary thickness of these outer plates and consequently the width of the traveling block as a whole.

Other features of this invention will appear as this description progresses.

The preferred embodiment of my invention is shown in the accompanying drawings wherein similar characters of reference designate corresponding parts and wherein:

Figure 1 is a view in side elevation of a traveling 45 block constructed in accordance with my invention.

Figure 2 is a horizontal sectional view of a cheek plate of my invention, taken on the line 2—2 of Figure 1, with parts left in elevation, illustrating, 50 in the preferred embodiment of my invention, the aperture in which the standing part of a compound pulley hoisting cable is installed in its attachment to the traveling block, and other details of my novel construction.

Figure 3 is a vertical sectional view taken on the line 3—3 of Figure 1, illustrating my preferred method of connecting the standing part of the cable to the traveling block.

Figure 4 is a vertical sectional view taken on 60 line 4—4 of Figure 1.

Figure 5 is an enlarged fragmentary view, partly in section and partly in side elevation, taken on the line 5—5 of Figure 1, illustrating the construction of my binding pin and plate spacing 65 means, and the relation of my tapered edge nuts to the tapered recesses provided therefor.

Figure 6 is an enlarged fragmentary view, partly in side elevation and partly in section, taken on the line 6—6 of Figure 4, illustrating my pin guid- 70 ing means.

Figure 7 is a sectional view of the structure shown in Figure 6, taken on the line 7—7 on Figure 6.

In the drawings:

With special reference to Figures 1 and 4, it will be seen that my traveling block comprises outer plates 8 and 9 between which are designed to be mounted a plurality of sheaves which may be designated 10 which are cored out on their sides so that the spokes or webs thereof are of a section substantially less than the section of the rims taken laterally.

These sheaves 10 are mounted upon a center shaft or pin 11 through the medium of roller bearings which may be generally designated 13 and which may be provided with lubricating passages 14 such as indicated in the drawings. The center pin or shaft 11 is secured in operative position by the nut 12.

Disposed in between each sheave and the next adjacent sheave 10 are plates which are substantially parallel with the outer plates 8 and 9 and with each other, and which are apertured to permit the passage of the center pin or shaft 11 therethrough.

These plates are designated by the numerals 15, 16, 17, and 18, and they are also apertured to receive the binding pins 19, 20, 21, and 22.

They are held in assembled position and in properly spaced relation through the medium of spacing collars 23 which are carried upon the pins 19, 20, 21 and 22 that likewise pass through the outer plates 8 and 9.

By reference to Figure 1, it will be noted that these pins 19 and 20 are disposed outside of the area, that is, the area circumscribed by the peripheries of the sheave members 10 and below points at a level coincident with the uppermost limits thereof.

Sheave supporting plate members of the framework including inner plates, are preferably provided, on sides thereof which face a sheave, with lading formations which project away from those sides toward the central plane of the sheave faced, and past a point coincident with the plane of the adjacent side edge of the rim of the sheave faced, so that each lading formation has a vertical face that is closer than the adjacent side edge of the rim of the sheave faced to a point coincident with the central plane of the latter.

Preferably these lading formations have portions symmetrically disposed on either side of the vertical plane coincident with the axes of the supported sheaves and on the lower halves of the portions of the sheave supporting frame plates which are circumscribed by the peripheries of the sheaves.

These lading formations may be embodied in the form of affixed members, such as the plates 24 which are secured to the sheave-supporting frame plates 15, 16, and 17 by rivets 25.

Again, these lading formations may be embodied in the form of integral projecting formations, such as the integral formations 8a and 9a on the sides of the sheave supporting frame plates 8 and 9 which face the sheaves adjacent thereto.

It will be obvious that the lading formations 24 may, if desired, take the form of integral formations, and that the integral formations 8a and 9a may likewise take the form of affixed formations, within the spirit of the invention.

Whether affixed or integral, these formations are preferably permanent complements of the individual sheave-supporting frame plates, which require no attention, adjustment or installation when assembling or disassembling the block.

The plate 18 is preferably devoid of any complementary lading formations, inasmuch as this plate is on the faster side of the traveling block

and this side will tend to travel more rapidly either in the up or down movement of the block, when it is not loaded.

The structure is such that the lower end portion of that side of the block which would normally tend to travel downwardly more slowly, when the block is unloaded, will have its weight supplemented by the lading means disposed thereon, which will tend to increase this speed of downward travel, by exerting the force of the dead weight of the lading formations and thereby causing the rope from the fast side of the block to be kept under tension and arrive quickly, and thus tend to avoid tilting.

It will be seen from this structure that I have produced a traveling block having sheave-supporting frame plates with sides which directly face the sides of the adjacent supported sheaves which have a predominantly greater weight symmetrically distributed over substantial portions of their areas below the axes of the supported sheaves in comparison with their areas above the axes of the sheaves.

This predominance of weight in the lower portions of these individual sheave-supporting frame plates is such as to produce a like predominance of weight in the lower portion of the traveling block as a whole in comparison with the upper part thereof.

Furthermore, it will be seen that I have achieved this predominantly greater weight in the lower portion of the structure without necessarily increasing the length of the traveling block below the axes of the sheaves beyond the length requisite to secure adequate stock in the sheave supporting frame plates to accommodate the load supporting attachment.

The complementary material which I have used to accomplish this predominantly greater weight in the lower portion of the traveling block in comparison with the upper part thereof, is, it will be apparent, disposed on and is a part of the sides of the sheave-supporting frame plates which directly face the supported sheaves.

It will, however, be understood that I may accomplish this object of obtaining a predominantly greater weight in the traveling block structure below the axes of the sheaves in comparison with a substantially equal length thereabove by cutting out substantial sections in that part of the plates above the said axes instead of by complementing the section of the plates below the axes.

It will likewise be understood that both means may be utilized to produce the desired predominance of weight in the block below the axes of the sheaves.

Before discussing the details of the binding pins 19, 20, 21, and 22 and their manner of connecting the plates 8 and 9 and the plates 15, 16, 17, and 18 together to form the framework of the traveling block, attention should be called to the fact that these pins and the spacing collars 23 serve to maintain an exactly spaced and rigidly bound assembly of the sheave-supporting plates of the traveling block frame-work to resist the development of warping and distortion in these plates under all conditions of use in the field.

This is particularly important in connection with the function of pins 21 and 22 and the spacing collars 23 and the fact that they hold the lower end edges of the sheave-supporting frame plates of the framework in a rigidly spaced and bound relationship thereby preventing the warping and distortion thereof during all phases of the manipulation and displacement of the lower

becket and its supporting pin when assembling and disassembling them.

In other words, these binding pins 21 and 22, and these spacing collars 23, are so related to the outer plates 8 and 9, and the intermediate plates 15, 16, 17, and 18, that this relation will remain fixed whether the becket pin 26 is in definite position and operatively supporting the becket 27 from the block or, whether it is removed entirely from the block, or whether it is merely loosely inserted therein.

The importance of this feature arises from the fact it then becomes readily feasible to loosen the becket pin or entirely withdraw it to disconnect the becket while maintaining without alteration in any way, of the relative positions of the various apertures through which the becket pin must pass when it is again to be inserted into the assembled position where it will support the becket.

Thus, the becket may be disconnected and reconnected at will, and with ease and rapidity and no time will be lost during such operations.

It will, of course, be understood that the becket pin 26 is secured in operative position by the nut 28.

It is quite a common practice in the drilling of wells to, at times during the operations, connect the standing part of the compound pulley hoisting cable to the traveling block as less load is thereby imposed on the well derrick than is the case when the standing part is anchored elsewhere.

This is particularly true when inserting long, heavy strings of well casing when the largest possible factor of safety is sought.

The usual practice has been to provide a becket upon the upper end of the traveling block which is mounted thereon by means of a pin disposed directly above the uppermost peripheral points of the sheaves thereof.

This necessarily results in an increase of the length of the traveling block structure and, particularly, decreases the available head room and therefore the effective, safe range of operation of the traveling block unit.

I have conceived that the available head room may be more fully utilized and that the effective, safe range of operation of a traveling block may be materially increased, with consequent advantages both in the use of large sheaves and in the use of small sheaves, by connecting the standing part of the hoisting cable to the traveling block within the area of the frame work thereof and at a point below the uppermost peripheral point of the sheave means thereof, and without the use of a conventional becket on the upper end of the traveling block.

As shown in Figures 1, 2, and 3, I have accomplished this by providing anchor means on the plate 8, which is the cheek plate on the slow side of the block.

By reference to Figures 1 and 3, it will be seen that this anchor means comprises a boss 29 which is preferably integrally formed within the lateral dimensions of the plate 8 and which is desirably "honda" shaped or "egg" shaped when seen in end elevation, as in Figure 1.

This boss 29 is preferably provided with a rope retaining groove 30 and it will be readily apparent that the loop 31 formed on the end of the standing part of a cable 32 may be placed over the outer end of the boss 29 and drawn upwardly into groove 30.

It is held in this position by means of a plate

33 which is preferably secured by screw bolts 34, 34 threaded into the outer side of the plate 8.

It will be noted that the plate 33 is L-shaped and that its horizontal leg 33a extends into position beneath the boss 29 and in such position that the loop 31 will be precluded from leaving the groove 30.

The parts of the cable forming the loop 31 are held together by means of clamps 35 which are disposed in the aperture 36 which is preferably integrally formed within the lateral limits of the plate 8.

In practice, the end of the standing part is passed downwardly through the aperture 36 and thence to the outside of the plate 8, where the loop 31 is formed and the clamps 35 are installed in operative position, after which the standing part is drawn upward through the aperture 36 until the loop 31 has passed into the groove 30 of the boss 29, and the plate 33 is then secured in operative position by the screw bolts 34, 34.

In the rear of the boss 29 and for a substantial distance around the area thereof, the plate 8 is provided with a thickened portion 37 which ensures that the boss will be supported by ample stock of metal to ensure adequate strength.

It will be seen from this description that the standing part of a compound pulley hoisting cable may be effectively secured to the slow side of my traveling block within the area thereof below a point coincident with the uppermost peripheral point of the contained sheave means and without the use of a top becket.

Thus the length of the traveling block is materially decreased and valuable additional head room is secured.

Furthermore, this is accomplished by a simple structure which is so located that the dead line or standing part of the cable may lead fairly thereto.

It will be understood that the pins 19, 20, 21, and 22, and the becket pin 26 pass through apertures in the outer plates 8 and 9, and also through apertures in the plates 15, 16, 17 and 18.

In traveling blocks for heavy duty, it is important that these pins fit the straight walls of their apertures closely.

At the same time, these pins being equipped with sharply angular shoulders, which must enter these apertures, have hitherto been difficult to assemble because of this very closeness of fit.

I have obviated this difficulty of assembly by providing each aperture with extensions which surround the sharply angular edges of the straight wall portions thereof, and which project outwardly from the lines which define the sides that bound the normal section of the plates to form bosses.

These bosses have apertures formed through their thickness which are funnel shaped, and which taper decreasingly from their outer lips to terminate at their inner ends at the ends of the straight wall apertures through the sheave-supporting frame plates.

One of these boss formations is preferably disposed at either end of each of the straight wall binding pin and becket pin apertures through the inner plates, and at the inner ends of those apertures through the outer plates, to serve as guides, so that these pins are readily steered into position.

Thus, with reference to Figure 7, it will be seen that the plates 17 and 18 are provided on either side thereof with annular plates 38 and 41 having funnel shaped mouths 38a and 41a, the

inner, smaller ends of which coincide with and upon a suitable surface and maintained upright thereon to facilitate reeving, changing or unreeving the hoisting rope therethrough.

It will be apparent that I have provided a traveling block of novel form.

For one thing, this traveling block is materially shortened, in comparison with traveling blocks normally used in well drilling operations.

This important advantage has been attained both by the elimination of the upper becket and by the attainment of the predominantly greater weight of the lower part of the traveling block in comparison with the upper part thereof. This predominantly greater weight in the lower portion of the block has been achieved by a substantial increase in the lateral direction, instead of lengthwise, of the cubical contents of individual sheave-supporting frame plates of the block, thereby obviating extra length on the lower end of the structure.

Furthermore, the upper portions of the cheek plates are, as will be noted, of less than normal cross-sections, which also helps to produce the predominance of weight in the mentioned lower portion of the block.

It will be apparent that this complementary material embodied in the individual sheave-supporting frame plates of the block is disposed to form projections extending from the normal interior lines of the frame plate structure, which also enables the maintenance of a restricted overall width of the block and utilizes hitherto unoccupied space therein by means of a novel construction.

It will also be apparent that I have provided a traveling block framework, the sheave supporting plates of which are rigidly spaced and bound together without the aid of the lower becket pin.

It will be obvious that this lower becket pin may be removed and re-inserted without the difficulties and delays commonly experienced with traveling blocks wherein this lower becket pin is utilized as a mean for holding the lower end of the framework against separation.

It will likewise be apparent that my structure is such that all pins utilized may fit closely in their apertures which have straight walls extending entirely through the normal cross sections of the frame plates through which they are formed.

Furthermore, it will be readily seen that all pins utilized may be inserted without difficulty, owing to the special interiorly disposed guiding means which I have provided therefor for progressively guiding them from an aperture through one of the outer frame plates into the apertures through the eyes of the becket, the inner frame plates and the spacing collars as the case may be, and thence into the aperture through the opposite outer frame plate.

In addition, it will be obvious that the pins which I utilize for securing the framework elements together, as well as the becket pin and the sheave-supporting pin, are firmly secured into operative position by means which may be flush with the outer faces of the cheek plates of the traveling block and which, at the same time, seat in their respective recesses in such a manner that cheek plates of minimum thickness may be used, with a consequent reduction in traveling block widths.

It will also be obvious that the binding and spacing means which maintain the sheave-supporting plates of my novel traveling block framework in rigidly bound and spaced relationship,

5 It will be noted that these funnel shaped mouths 38a and 41a are reversely beveled so that these plates may be placed either in the position shown or they may be reversed so that the mouths 41a are on the left hand side.

10 In any event, with this structure, when it is sought to introduce the pin 26 into its proper position of assembly, it will readily enter the outer lips of the funnel shaped mouths 38a or 41a and be steered into the straight walls of the apertures 39 of the plates.

15 The same structure may be utilized in all of the plates, and it will, of course, be understood that the annular plates 38 and 41, which are secured to the respective frame plates by the rivets 40 and by welding, as at 40a in Figure 6, 20 may be replaced by integral boss formations projecting outwardly from the lines defining the sides bounding the normal cross section of the plates 15, 16, 17 and 18 to constitute like extensions in which funnel shaped mouth pin guide 25 means may be formed, and thus maintain the straight wall portions of the apertures across the full normal cross section of the metal of the plates.

30 The inner sides of the outer plates 8 and 9, in addition to the formations 8a and 9a, are provided with integrally formed boss formations 42 and 43 which project away from the lines defining the inner sides of the normal cross sections 35 of these plates toward a point coincident with the central planes of the adjacent sheaves which have plane face sides directly facing the said inner sides of the said plates.

These bosses 42 and 43 have funnel shaped 40 apertures 42a and 43a formed through their thicknesses which decrease in taper toward and terminate at the ends of the straight walls of the apertures 44 and 45 formed through these plates 8 and 9, respectively, for the reception of the becket pin 26. The funnel shaped mouths or 45 apertures 42a and 43a likewise facilitate the insertion of the becket pin 26.

This structure will be readily understood by reference to Figure 4 of the drawings where 50 the pin 26 is shown secured in operative position by means of the nut 28.

By reference to Figures 4 and 5 of the drawings it will be noted that the pin 19 is provided with threaded portions upon each end thereof.

55 This is true of all of the pins 19, 20, 21 and 22. These threaded portions are adapted to lie within the tapered recesses 46 formed in the outer side walls of the outer plates 8 and 9.

These tapered recesses 46 are adapted to receive the nuts 47 having tapered edges 48, which 60 nuts 47 are designed to be screwed upon the threaded ends of the pin 19 until their edges 48 assume a seating contact with the tapered walls of these recesses 46. When the structure is 65 assembled, the said seating contact will result in the utilization of the greater portion or all of the stock of the outer plates for useful work and will, therefore, render possible the use of outer plates of less thickness than would otherwise be necessary.

70 This tends to reduce the width of the traveling block as a whole.

It will also be noted that the outer plates 8 and 9 are provided with flattened lower edges 49 75 so that the traveling block may be readily stood

independently of becket pins and sheave-supporting pins or shafts, is perfectly adapted to constructions embodying the conventional pin or shaft for supporting sheaves therein, such as illustrated in the accompanying drawings.

It will, furthermore, be manifest that this structure is equally adapted to and embodies important advantages when utilized in conjunction with traveling block sheave assemblies where-in each sheave has independently rotatable supporting means, such as, among others, the structure described and claimed in my co-pending application for United States Letters Patent, Serial No. 485,275, filed September 29th, 1930.

It is obvious that there are other advantages of my structure which need not be detailed at this point and some of which will appear in the claims appended hereto.

I claim:

1. A traveling block construction for well drilling operations comprising a plurality of sheave members, a framework for supporting said sheave members, means for rotatably supporting said sheave members therein, a plurality of spaced plates, and lading means carried by said spaced plates disposed in the lower half of the area of the structure circumscribed by the said sheaves.

2. A traveling block construction for well drilling operations comprising a plurality of sheave members, a framework for supporting said sheave members, means for rotatably supporting said sheave members therein, a plurality of spaced plates, and lading means on one of said spaced plates and positioned facing the sides of adjacent sheaves.

3. A traveling block construction for well drilling operations comprising a plurality of sheave members, a framework for supporting said sheave members, means for rotatably supporting said sheave members therein, a plurality of spaced plates, and lading means carried by certain of said spaced plates, the spaced plates nearest the fast side of said traveling block being not laden.

4. A traveling block construction for well drilling operations comprising a plurality of sheave members, a framework for supporting said sheave members, means for rotatably supporting said sheaves therein, and means for increasing the weight of the said traveling block below the axes of the sheaves in comparison with the weight of said traveling block above said axes, said means being located more on the slow side of said traveling block than on the fast side thereof.

5. In means to predominantly lade one side of a traveling block in comparison with the other side thereof, a plate for use in a traveling block construction having a side adapted to face a sheave in a block assembly and provided with a lading formation disposed intermediate its ends and projecting from the said side.

6. In means to predominantly lade one side of a traveling block in comparison with the other side thereof, a sheave supporting plate having an aperture adapted to receive load supporting means and an aperture adapted to accommodate sheave supporting means, and lading means on the plate as a part thereof, the said lading means being formed and proportioned so as to be disposed between the load supporting means aperture and the sheave supporting means aperture and occupying a position in the lower half of said plate.

7. A traveling block construction for well drilling operations comprising a plurality of sheave members, a framework for supporting said sheave

members, means for rotatably mounting said sheave members therein, and lading means within the peripheral limits of the sheaves and disposed symmetrically of a vertical plane co-incident with the axes of the sheaves for increasing the weight of that portion of the traveling block below the said axes with relation to that portion above the said axes.

8. A traveling block construction for well drilling operations comprising a plurality of sheave members, a framework for supporting said sheave members, means for rotatably supporting said sheave members therein, portions of said framework being thicker below the axes of said sheaves than above said axes to increase the weight of the portion of the traveling block below said axes in relation with the portion of said traveling block above said axes.

9. An elongated plate for traveling block construction having an aperture for the reception of means to rotatably support an associated sheave having one of its ends adapted for the reception of load supporting means, and characterized by having a portion thicker below the axis of an associated sheave than above the said axis which produces a predominance in the weight of the portion thereof below the said axis in relation to the weight of the portion thereof above the said axis.

10. A traveling block construction for well drilling operations comprising a plurality of sheave members, a framework comprising sheave supporting plate members for supporting said sheave members, and means for rotatably mounting said sheave members therein, some of the sheave supporting plate members of the said framework having portions below the axes of the said sheaves predominantly laden by complementary supplements to the cross sections thereof.

11. An elongated plate for traveling block construction the normal cross section of which is defined by lines which permit the free rotation of associated sheave means disposed on either side thereof and having an aperture adapted for the reception of means to rotatably support associated sheave means and characterized by complementary supplements to the cross section thereof which produce a predominance in the weight of the portion thereof below the axes of the said associated sheave means in relation to the weight of the portion thereof above the said axes.

12. A traveling block construction for well drilling operations comprising a plurality of sheave members, a sheave supporting framework for supporting said sheave members, said traveling block having its sheave supporting framework portion below the axes of said sheave members of substantially the same area as that part of its sheave supporting framework portion above the axes of said sheave members, said portion below the axes being of predominantly greater weight than said portion above the axes of said sheave members.

13. A vertically elongated plate for traveling block construction apertured between its ends to receive sheave supporting means and apertured at one of its ends to receive load supporting means, having its weight per unit of length and width of a substantial portion of the plate between the lower end thereof and a line at right angles to the longitudinal axis of the plate and co-incident with the center of the aperture to receive sheave supporting means predominantly greater than the weight per unit of length and width of an equal area of the portion of the plate

- between said line and the upper end thereof, whereby the center of gravity of the said two portions of the said two areas of the plate taken together is a substantial distance below the said line.
14. A plate for a traveling block framework apertured between its ends for the reception of means for rotatably associating a sheave therewith, the cubical contents of a substantial part of the plate co-incident with a unit of area of that portion of the plate to be described by the periphery of an associated sheave being predominantly greater than the cubical contents of another part of the same portion of the plate coincident with an equal unit of area thereof, the material constituting the said predominantly greater cubical contents of the first said part of the said portion of the plate being formed and adapted to be disposed interiorly of a traveling block framework.
15. A plate for a traveling block framework apertured between its ends to receive sheave supporting means, and apertured at one of its ends to receive load supporting means, the cubical contents of the plate per average unit of width and length in the area between the lower end thereof and a line at right angles to the longitudinal axis of the plate and coincident with the center of the aperture to receive sheave supporting means being predominantly greater than the cubical contents of the plate per average unit of length and width in the area between the said line and the other end of the plate whereby to predominantly lade the first said end thereof in comparison with the second said end.
16. An elongated plate for traveling block construction having an aperture between its ends for the reception of means to rotatably support an associated sheave, and having means on one of its ends adapted to receive load-supporting means, the cubical contents of the square area of the upper end portion thereof which is defined by its edge extremities and a transverse line co-incident with the axial center of the said aperture being substantially less than the cubical contents of an equal square area on the lower end portion thereof bounded on one of its sides by the said line.
17. An elongated plate for traveling block construction having an aperture adjacent to its longitudinal center for the reception of means to rotatably support an associated sheave and having a portion on its lower end adapted to receive a load supporting attachment, the square areas of the respective ends of the plate on either side of a transverse line through the axial center of the said aperture, exclusive of the square area of the said portion, being substantially equal, and the lower end, exclusive of the said portion, having a predominantly greater cubical content than the upper end.
18. In a traveling block construction, a plurality of plates, parallel sheaves interposed in alternating relation to the said plates and supported thereby and each having a grooved periphery terminating in edge portions at the respective sides thereof, each of the said plates having a side directly facing a side of an adjacent sheave, and a projecting formation extending therefrom toward a point co-incident with the central plane of the said adjacent sheave and beyond a point co-incident with the plane of an adjacent peripheral edge portion thereof.
19. A plate for traveling blocks having one or more sides adapted to directly face the plane
- face sides of sheaves means associated therewith and having a plurality of apertures formed transversely of its cross section including an aperture adapted for the reception of means to rotatably support associated sheave means and other apertures adapted for the reception of pin means including an aperture adapted to receive a part of a load supporting attachment, all of the last said apertures being positioned relative to the first mentioned aperture so that pin means received therein are disposed beyond the peripheral limits of associated sheave means, said plate having a plurality of projecting formations extending from the said one or more sides some of which extend from points on the plate within the area to be described by the peripheries of associated sheave means and some of which extend from points thereon outside of the said area, the projecting formations extending from points below a line at right angles to the vertical axis of the plate and coincident with the center of the first mentioned aperture being predominantly heavier than the projecting formations extending from points thereon above the said line.
20. In a traveling block construction, a plurality of sheaves, each having a grooved periphery terminating in an edge on either side thereof, a plurality of frame plates each of which has a side facing the said sheaves, and projecting formations extending from the said sides toward a point coincident with the central plane of the sheave faced, each of the said formations having a vertical face positioned closer than the adjacent side edge of the periphery of the sheave faced to a point coincident with the central plane of the said sheave.
21. A cheek plate for traveling blocks consisting of a vertically elongated member devoid of angular projections on its outer face, the member having means adapted for the attachment of the standing part of a hoisting cable thereto, the said plate having a passage adapted to receive sheave supporting means and a plurality of passages, certain of which latter are adapted to receive binding pins and another of which is adapted to receive a load supporting pin, all of said binding pin and load supporting pin receiving passages being positioned relative to the sheave supporting means passage so that same are adapted to be disposed beyond the periphery of a supported sheave the diameter of which is such as to closely approach the opposite side edges of the member and the upper edge thereof, and having projecting formations extending from the inner face thereof.
22. A cheek plate for traveling blocks consisting of a vertically elongated member devoid of angular projections on its outer face, the member having means adapted for the attachment of the standing part of a compound pulley hoisting cable thereto, the said plate having a passage adapted to receive sheave supporting means, and a plurality of passages certain of which latter are adapted to receiving binding pins and another of which is adapted to receive a load supporting pin, all of said binding pin and load supporting pin receiving passages being positioned relative to the sheave supporting means passage so that same are adapted to be disposed beyond the periphery of a supported sheave the diameter of which is such as to closely approach the opposite side edges of the member and the upper edge thereof, and having projecting formations extending from the inner face thereof, some of the said projecting formations being disposed in the

lower half of the area to be described by the periphery of an associated sheave and some of the said projections being disposed outside of the said area, the projecting formations extending from the portion of the plate below the center of the said passage adapted to receive sheave supporting means being predominantly heavier than the the projecting formations extending from the portion of the plate above the said center of the said passage.

23. An elongated plate for traveling block construction adapted to be disposed between two associated sheaves apertured for the reception of means adapted to rotatably support sheaves, the normal cross section of the said plate being defined by lines which permit the free rotation of an associated sheave on either side thereof, and having projecting formations extending beyond the sides thereof toward points co-incident with the central planes of associated sheaves, including projecting formations extending from the major portion of the lower halves of the areas to be described by associated sheaves, at least one end of the plate being adapted for the reception of load supporting means.

24. A plate for traveling blocks having one or more sides adapted to directly face the plane face sides of sheave means associated therewith and having a plurality of apertures formed transversely of its cross section including an aperture adapted for the reception of means to rotatably support associated sheave means and other apertures adapted for the reception of pin means including an aperture adapted to receive a part of a load supporting attachment, all of the last said apertures being positioned relative to the first mentioned aperture so that pin means received therein are disposed beyond the peripheral limits of associated sheave means, said plate having a plurality of projecting formations extending from the said one or more sides some of which extend from points on the plate within the area thereof to be described by the peripheries of associated sheave means and some of which extend from points thereon outside of the said area, the said projecting formations being positioned relative to the first said aperture so that the portion of the plate below a line at right angles to the vertical axis of the plate and co-incident with the center of the said first said aperture is predominantly heavier than the portion thereof above the said line.

25. A plate for traveling blocks having one or more sides adapted to directly face the plane face sides of sheave means associated therewith, the body of which is characterized by the contour of portions of the edges that define its length and width comprising portions of the edges bounding it on one end which conform substantially to parallel lines and a rectilinear edge portion bounding the said end thereof, said plate having an opening adapted to receive means for rotatably supporting a sheave, said opening being so disposed that the axial center thereof is substantially equidistant from the three said edge portions so that when the plate is associated with a sheave having a diametrical dimension approximately equal to the width between the said parallel edge portions of the said end thereof the periphery of the sheave will occupy substantially the same relative position with respect to the said end edge portion that it occupies with respect to either of the said parallel edge portions, by having a short portion at the opposite end of the plate extending a distance from the said axial center of

the said opening slightly in excess of the distance between the said axial center of the said opening and the first said end, said short portion having an aperture adapted to receive a part of a load supporting attachment, and, by having projecting formations extending beyond the normal cross section thereof and toward the central plane of associated sheave means.

26. A traveling block construction for well drilling operations comprising a plurality of sheave members, a framework for supporting said sheave members and including a plurality of plates having aligned apertures, means for rotatably supporting said sheave members therebetween, a removable pin projecting through said apertures and boss means disposed on the sides of the said plates which face toward sides of the said sheaves, said boss means having funnel-shaped mouths which taper decreasingly from their outer faces to terminate at the ends of the said aligned apertures for progressively guiding said pin into said apertures interiorly of the said framework.

27. A traveling block construction for well drilling operations comprising a framework made up of a plurality of parts having apertures there-through, a pin designed to have a close fit in such apertures, the said pin having an angular shoulder formed thereon, each of the said apertures having on the ends thereof which terminate interiorly of the said framework means to facilitate the progressive introduction of said pin shoulder into said apertures, the said means being disposed outside of the lines which define the normal cross section of the said parts of the said framework.

28. A traveling block construction for well drilling operations comprising a plurality of sheave members, a framework including plates, means for rotatably supporting said sheave members therein, the said plates having a plurality of sets of aligned apertures adjacent the lower end edges thereof, spacing means disposed alternately between the said plates, pin means disposed through some of the said apertures and co-operable with the said spacing means for exactly spacing and rigidly binding the said lower end edges together, means to secure the said pin means in operative position, a becket, pin means disposed through other of the said apertures for the support of the becket, and means to secure the last said pin means in operative applied position.

29. A traveling block construction for well drilling operations comprising a plurality of sheave members, a framework comprising plates, means for rotatably supporting said sheave members therein, the said plates having a plurality of sets of aligned apertures formed therethrough at points adjacent the lower end edge portions thereof, spacing means disposed alternately between the said plates, pin means disposed through some of the said apertures and co-operable with the said spacing means for exactly spacing, rigidly binding together, and maintaining the said lower end edge portions through which the said apertures are formed in alignment, means for maintaining the said pin means in applied operative position, a becket, pin means disposed through other of the said apertures for the pivotal support of the becket, means to secure the last said pin in operative applied position, and means to secure the upper end edge portions of the said plates in rigidly aligned, spaced and bound relationship.

30. A traveling block construction for well drilling operations comprising a framework, a pin

projecting through said framework and terminating within the width thereof in apertures in said framework, each of which apertures has a tapered wall portion and a straight wall portion, and a tapered nut threaded onto each end of said pin and screwed into seating contact with tapered wall portions of the said apertures.

31. In sheave block construction, a pair of cheek plates, a binding pin, the said cheek plates having openings therein including straight wall portions of substantially the same diameter as the pin so as to receive and support said pin, and the said pin having threaded ends extending beyond said first named portions of the openings and into flared enlargements of the openings, and threaded nuts with flared edges adapted to engage said threaded ends and to be screwed into seating relation with said flared portions of said openings.

32. In sheave block construction, a pair of cheek plates, a binding pin, the said cheek plates having openings therein including straight wall portions of substantially the same diameter as the pin so as to receive and support said pin, and the said pin having threaded ends extending beyond said first named portions of the openings and into flared enlargements of the openings, and threaded nuts with flared edges adapted to engage said threaded ends and to be screwed into seating relation with said flared portions of said openings, the outer extremities of said pins and said nuts being within the contour lines of the outer faces of said cheek plates.

33. A traveling block construction for well drilling operations comprising a plurality of sheave members, a framework including plates for supporting said sheave members, and means for connecting the standing part of a hoisting cable to said traveling block, said last named means having its effective anchorage disposed at a level below the upper peripheral surfaces of said sheave members and within the lateral limits of an outermost plate of said framework.

34. A traveling block construction for well drilling operation comprising a sheave, a framework including plates for supporting said sheave, said framework terminating at its top at the periphery of the said sheave, and anchorage means for connecting the standing part of a hoisting cable to said traveling block, said last named means being disposed within symmetrical contour lines of the said framework and carried wholly by one of the said plates.

35. A traveling block structure comprising a plurality of plates having different sets of aligned apertures formed therethrough to respectively engage binding pin means, load supporting means and sheave supporting means, spacer elements disposed between said plates to space them apart, a plurality of binding pins to extend through some of said apertures for binding said plates in said spaced relation, means for securing said binding pins in operative position, sheave means disposed between said plates, means disposed through some of the apertures in said plates to rotatably support said sheave means, three edges of said plates extending to points substantially co-incident with the peripheral limit of the said sheave means, and other edges of said plates extending to a point beyond the said peripheral limit to engage load supporting means, said binding pins being disposed on opposite sides and opposite ends of said structure and outside of the area circumscribed by the said peripheral limit of the sheave means and being entirely independent of the sheave supporting means and the load supporting means, and anchorage means to engage the standing part of a compound pulley hoisting rope, said anchorage means being disposed within the lateral limits of one of said plates.

36. A traveling block structure comprising a plurality of plates having different sets of aligned apertures formed therethrough to respectively engage binding pin means, load supporting means and sheave supporting means, spacer elements disposed between said plates to space them apart, a plurality of binding pins to extend through some of said apertures for binding said plates in said spaced relation, means for securing said binding pins in operative position, sheave means disposed between said plates, means disposed through some of the apertures in said plates to rotatably support said sheave means, three edges of said plates extending to points substantially co-incident with the peripheral limit of the said sheave means, and other edges of said plates extending to a point beyond the said peripheral limit to engage load supporting means, said binding pins being disposed on opposite sides and opposite ends of said structure and outside of the area circumscribed by the said peripheral limit of the sheave means and being entirely independent of the sheave supporting means and the load supporting means, and anchorage means to engage the standing part of a compound pulley hoisting rope, said anchorage means being disposed within the lateral limits of one of said plates.

pendent of the sheave supporting means and the load supporting means, and anchorage means to engage the standing part of a compound pulley hoisting line, said anchorage means being disposed within symmetrical contour lines of the 5 said structure.

37. A traveling block structure comprising a plurality of plates having different sets of aligned apertures formed therethrough to respectively engage binding pin means, load supporting means and sheave supporting means, spacer elements disposed between said plates to space them apart, a plurality of binding pins to extend through some of said apertures for binding said plates in said spaced relation, means for securing said binding pins in operative position, sheave means disposed between said plates, means disposed through some of the apertures in said plates to rotatably support said sheave means, three edges of said plates extending to points substantially co-incident with the peripheral limit of the said sheave means, and other edges of said plates extending to a point beyond the said peripheral limit to engage load supporting means, said binding pins being disposed on opposite sides and opposite ends of said structure and outside of the area circumscribed by the said peripheral limit of the sheave means and being entirely independent of the sheave supporting means and the load supporting means, and anchorage means to engage the standing part of a compound pulley hoisting rope, said anchorage means being disposed within the area of the said structure.

38. A traveling block structure comprising a plurality of plates having different sets of aligned apertures formed therethrough to respectively engage binding pin means, load supporting means and sheave supporting means, spacer elements disposed between said plates to space them apart, a plurality of binding pins to extend through some of said apertures for binding said plates in said spaced relation, means for securing said binding pins in operative position, sheave means disposed between said plates, means disposed through some of the apertures in said plates to rotatably support said sheave means, three edges of said plates extending to points substantially co-incident with the peripheral limit of the said sheave means, and other edges of said plates extending to a point beyond the said peripheral limit to engage load supporting means, said binding pins being disposed on opposite sides and opposite ends of said structure and outside of the area circumscribed by the said peripheral limit of the sheave means and being entirely independent of the sheave supporting means and the load supporting means, and anchorage means to engage the standing part of a compound pulley hoisting rope, said anchorage means being disposed within the lateral limits of one of said plates.

39. A traveling block structure comprising plates, rotatable sheaves supported by and between said plates, becket means disposed on one of the ends of said structure and supported 6 thereon by pin means disposed in apertures through said plates, the other of the ends of said plates terminating at a distance from the axis of said sheaves substantially co-incident with the peripheries of said sheaves, and anchorage means for the standing part of a compound pulley hoisting line at the last said end and having its effective point within the area described by the peripheries of said sheaves and

disposed within the lateral limits of said structure.

39. A traveling block structure comprising plates, rotatable sheaves supported by and between said plates, becket means disposed on one of the ends of said structure and supported thereon by pin means disposed in apertures through said plates, the other of the ends of said plates terminating at a distance from the axis of said sheaves substantially co-incident with the peripheries of said sheaves, and anchorage means for the standing part of a compound pulley hoisting line at the last said end and having its effective point within the area described by the peripheries of said sheaves and disposed within symmetrical contour lines of said structure.

40. A plate for traveling blocks, the body of which is characterized by the contour of portions of the edges that define its length and width comprising portions of the edges bounding it on one end which conform substantially to parallel lines and a rectilinear edge portion bounding the said end thereof, said plate having an opening adapted to receive means for rotatably supporting a sheave, said opening being so disposed that the axial center thereof is substantially equidistant from the three said edge portions so that when the plate is associated with a sheave having a diametrical dimension approximately equal to its width between the said parallel edge portions thereof the periphery of the sheave will occupy substantially the same relative position with respect to the said end edge portion that it occupies with respect to either of the said parallel edge portions, by having a short portion at the opposite end thereof extending a distance from the said axial center of the said opening slightly in excess of the distance between the said axial center of the said opening and the first said end, and having an aperture adapted to receive a part of a load supporting attachment, by having a portion on either side of the center of the first said end apertured for the reception of binding pins therethrough, and further characterized by having anchorage means for connecting the standing part of a hoisting cable

thereto, the last said means being disposed wholly within the body thereof.

41. A cheek plate for traveling blocks consisting of a vertically elongated member having means adapted for the attachment of the standing part of a hoisting cable, the last said means being disposed interiorly thereof.

42. A cheek plate for traveling blocks consisting of a vertically elongated member devoid of angular projections on its outer face, the member having means adapted for the attachment of the standing part of a hoisting cable thereto, the said means being disposed interiorly thereof.

43. A cheek plate for traveling blocks consisting of a vertically elongated member devoid of angular projections on its outer face, the member having means adapted for the attachment of the standing part of a hoisting cable thereto, the said plate having a passage adapted to receive sheave supporting means and a plurality of passages, certain of which latter are adapted to receive binding pins and another of which is adapted to receive a becket supporting pin, all of said binding pin and becket pin receiving passages being positioned relative to the sheave supporting means passage so that same are adapted to be disposed beyond the periphery of a supported sheave the diameter of which is such as to closely approach the opposite side edges of the member and the upper edge thereof.

44. A cheek plate for traveling blocks characterized by a body portion having an aperture to accommodate one end of a sheave supporting member, the said plate having three edges equidistantly related to the said aperture and an edge defining a load supporting end, the last said end being disposed a greater distance away from the said aperture than any of the said three edges and being provided with an aperture to receive one end of a pin of load supporting means, the said plate having other apertures adapted for the terminal reception of binding pins, and anchorage means for the standing part of a hoisting cable, the last said means being disposed wholly within the body of the plate.

HARRY TALMAGE NICHOLS.
